A. NEWCOMB, OF SHIPMAN, ILLINOIS.

Letters Patent No. 86,242, dated January 26, 1869.

COMBINED DOOR-BOLT AND WEATHER-STRIP.

The Schedule referred to in these Letters Patent and making part of the same.

To all whom it may concern:

Be it known that I, A. NEWCOMB, of Shipman, in the county of Macoupin, and State of Illinois, have invented a new and useful Improvement in Combined Door-Bolt and Weather-Strip; and I do hereby declare that the following is a full, clear, and exact description thereof, which will enable others skilled in the art to make and use the same, reference being had to the accompanying drawings, forming part of this specification, in which—

Figure 1 represents a side elevation of the sliding bolt, with the strip attached to it, and

Figure 2 represents a transverse sectional elevation of the same.

Similar letters of reference indicate like parts.

The object of this invention is to provide a weather-strip that may be actuated to open or close by the action of a common door-bolt, when the same is moved to fasten or unfasten the door.

The weather-strip, which is of an ordinary construction, is arranged in a slot in the lower end of the door, and connected to an ordinary sliding bolt, which I prefer to arrange at about the centre of the door, at the bottom, so that, when the bolt is raised, it will raise the strip, and, when closed, will lock the door to the threshold upon the inside, and apply the weather-strip to the same upon the outside.

A represents the door, and

B, the threshold, which I prefer to provide with a recess on the outside, as shown in fig. 2.

C represents the sliding bolt, secured to the inside of the door, and provided with an arm, D, projecting into a groove in the side of the door.

The door is provided with a deep, narrow groove in the end, running from edge to edge, the inner wall of

which is designed to be coincident with the vertical wall of the recess in the threshold, when the door is shut.

E represents the weather-strip, which is suspended by a slot, in the upper edge, from the arm D.

The strip E, and the bolt D, are so arranged, with reference to each other, that, when the bolt is shoved down, to lock the door, the strip will be shut down in the recess of the threshold, as shown in fig. 2, and when the bolt is drawn up, the strip will be raised sufficiently above the shoulder of the recess of the threshold as to admit the door to be opened.

The threshold need not be recessed unless preferred, as the strip may be allowed to rest on the top of it, or it may drop into a groove in the threshold.

The mortise in the strip, for the reception of the arm D, is made of sufficient length to admit sufficient play of the parts to compensate for any variations of their relative positions that may occur when either closed or open.

Having thus described my invention,

I claim as new, and desire to secure by Letters Patent—

The arrangement of the bolt C, arm D, and slotted weather-strip E, with reference to each other, the recessed door A, and the mortised and recessed threshold B, whereby the downward movement of the bolt locks the door to the threshold upon the inside, and applies the weather-strip to the same upon the outside, as herein shown and described for the purpose specified.

A. NEWCOMB.
